(57) **CLAIM**

The ornamental design for an external case for a wearable medical device, as shown and described.

DESCRIPTION

FIG. 1 is a front perspective view of an external case for a wearable medical device in accordance with the present invention;

FIG. 2 is a front side plan view thereof;

FIG. 3 is a rear side plan view thereof;

FIG. 4 is a right side plan view thereof;

FIG. 5 is a left side plan view thereof;

FIG. 6 is a top plan view thereof;

FIG. 7 is a bottom plan view thereof;

FIG. 8 is a front perspective exploded view thereof; and,

FIG. 9 is a rear perspective exploded view thereof.

The broken lines illustrating portions of the external case for a wearable medical device form no part of the claimed design.
